UNITED STATES PATENT OFFICE.

EDWARD F. HEFFERNAN, OF LOCKPORT, NEW YORK, ASSIGNOR TO
ROBERT JOHN QUIGLEY, OF TORONTO, CANADA.

WATCH-CASE HINGE.

SPECIFICATION forming part of Letters Patent No. 319,814, dated June 9, 1885.

Application filed May 17, 1884. (No model.)

To all whom it may concern:

Be it known that I, EDWARD F. HEFFERNAN, of Lockport, in the county of Niagara, in the State of New York, now residing at the 5 city of Toronto, in the county of York, Province of Ontario, Canada, have invented certain new and useful Improvements in Hinges for Watch-Cases; and I do hereby declare that the following is a full, clear, and exact description thereof, reference being had to the accompanying drawings, in which--

Figure 1 is a perspective view of the center and bezel of a watch-case containing my improvements separated from each other. Fig. 15 2 is a vertical section of the same united upon a line passing through the hinge, the bezel being opened outward. Fig. 3 is a like view of said parts, with said bezel closed; and Fig. 4 is a horizontal section of said case-center 20 upon a line passing through the axis of said hinge.

Letters of like name and kind refer to like parts in each of the figures.

This invention relates to the hinge-joint for 25 a watch-case covered by Letters Patent No. 288,184, issued November 6, 1883, and reissued August 26, 1884, No. 10,517, and has for its object the lessening of the expense of construction and an increase in the strength and 30 durability of the parts of the joint; to which end my said invention consists, principally, in the means employed for forming the pivot-pin bearing within the case-center, substantially as and for the purpose hereinafter specified.

It consists, further, in the means employed 35 for limiting the motion of the bezel when opened, and for preventing injury to and strain of the hinge, substantially as and for the purpose hereinafter shown.

In the application of my improvement I take an ordinary watch-case center, A, and in and through the bearing *a* for the back or bezel cut a rectangular opening, *a'*, as shown.

45 At a point below the opening *a'* and parallel with its outer edge, a round opening, *a''*, is drilled through the center A in a line parallel with the planes of the sides of said center, and into said opening is inserted a metal tube, 50 B, that has such diameter of interior as to enable it to receive and contain a pin having

the size usually employed for hinge-joints. The body of said tube is contained within the recessed interior of said case-center, with its outer side bearing against the contiguous portion of said part, and in such position is secured by means of solder, after which portions of said tube are removed upon a line with each end of said opening *a'*, so as to leave three sections of the same, one at the center of said opening, and one at each end of the same, which extend outward to the periphery of the case-center.

55 A bezel, C, is fitted to the center A in the usual manner, and at a suitable point is provided with two lugs, *c*, which have the form shown in Fig. 2, and are adapted to be inserted within the opening *a'*, and to fit with reasonable closeness within the same and between the sections of the tube B.

60 Each lug *c* is provided with an opening, *c'*, which corresponds in size to the opening *b* of the tube B, and when the bezel C is closed down upon the case-center said openings coincide and enable a hinge-pin, D, to be passed 65 through them, so as to connect said center and bezel and enable the latter to be swung open and closed in the usual manner.

70 In consequence of the length and shape of the hinge-lugs *c* the bezel C, when opened, is lifted from off the center A and carried outward until its edge in rear of said lugs laps over and bears against the outer face or periphery of said center, as in the hinge-joint covered by the patent before referred to, and 75 operates to limit the outward movement of said bezel. As, however, the impingement of said bezel upon said center tends to injure or break the connection between the former and said hinge-lugs, I provide an additional stop 80 by extending each lug *c* inward beyond its pivotal bearing, as shown, and forming at its inner end a tail, *c''*, which, when said bezel is opened outward, impinges upon said center A immediately in front of the opening *a'*, and 85 operates to prevent further motion of said lug in such direction. By this arrangement each lug is limited in its motion independent of the bezel, while the impingement of the latter upon the periphery of the case-center causes 90 its motion to be arrested without interference with or strain upon said lugs.

Having thus described my invention, what I claim is—

1. As an improvement in hinge-joints for watch-cases, a tube inserted within or through the case-center to furnish a bearing for the hinge-pin, substantially as and for the purpose specified.
2. As an improvement in hinge-joints for watch-cases, a case-center having inserted within one side a tube which is adapted to receive a hinge-pin, and is cut away at or near its longitudinal center to admit of the insertion of hinge lug or lugs, substantially as and for the purpose shown.
3. As an improvement in hinge-joints for watch-cases, a hinge-lug which is provided with an inwardly-extending tail that is adapted

to impinge upon the case-center when the bezel is opened and limit farther motion in such direction, substantially as and for the purpose set forth.

4. The case-center A, provided with the rectangular opening a' , round opening a'' , and sectional tube B, the bezel C having attached thereto lugs c, which have the form shown, and are each provided with a tail, c' , in combination with each other and with the pin D, substantially as and for the purpose shown and described.

Toronto, May 9, 1884.

E. F. HEFFERNAN.
In presence of—
CHAS. C. BALDWIN,
JOHN G. RIDOUT.
